UNITED STATES PATENT OFFICE.

CECIL WALTER PAGET, OF SUTTON BONNINGTON, ENGLAND.

LOCOMOTIVE.

No. 806,178.

Specification of Letters Patent.

Patented Dec. 5, 1905.

Application filed September 1, 1905. Serial No. 276,727.

To all whom it may concern:

Be it known that I, CECIL WALTER PAGET, engineer, a subject of the King of Great Britain, residing at Sutton Bonnington, Loughborough, England, have invented certain new and useful Improvements in Locomotives, of which the following is a specification.

According to this invention the locomotive has three crank-axes, each having four cranks and eight single-acting steam-cylinders connected in pairs, two pairs being between each outer axle and the middle axle. The cylinders of each pair are not in line with each other, but their inner ends communicate. The four cranks of the middle axle are connected by rods to pistons working in four of the cylinders, one of each pair. These four pistons have rods fixed to them, which pass through stuffing-boxes in the inner ends of the cylinders and are connected by frames to pistons working in four idle cylinders situated outside the outer axles. The four latter pistons are respectively connected by rods to two of the cranks of each of the outer axles. The two remaining cranks of each of the outer axles are connected by rods to pistons in the other cylinders of the four above-mentioned pairs of steam-cylinders. By this arrangement the three axles are coupled together, and side coupling-rods are rendered unnecessary. The moving parts of the engine also approximately balance each other. Steam is admitted to the steam-cylinders by rotary valves and is exhausted from them through ports uncovered by the pistons.

Figure 1 is a vertical section, and Fig. 2 a horizontal section, of part of a locomotive-engine constructed as above described.

1, 2, 3 are the three crank-axes, each having four cranks.

4, 5, 6, 7 are four pairs of single-acting cylinders, with the two cylinders in each pair back to back and opening one into the other, but not in line. The pistons of the two innermost cylinders of the pairs 4, 5 are connected by rods with two opposite cranks on the crank-shaft 1. Similarly, the piston of one of the cylinders of each of the pairs 6, 7 is coupled by a rod to one of the cranks of the shaft 3. The pistons of the other cylinders of the four pairs are connected by rods with four cranks on the central crank-shaft 2. The pistons of these latter cylinders also have rods 8, 9 extending from them through stuffing-boxes 10, and extensions of these rods are arranged to drive the two other cranks on the

shafts 1 and 3. Preferably this is effected as above described and as is shown in the drawings by the rods being connected by open frames 11, 12 to sliding blocks or pistons 13, 14, 60 which work to and fro in cylindrical guides 15, 16, and by the sliding blocks being coupled by connecting-rods to the cranks; but it might be effected in other ways. The two outermost cranks on the shaft 2 are opposite to one another and at right angles to the two innermost cranks.

17 represents rotating valves for controlling the admission of steam to the pairs of cylinders. One such valve is, as partially shown, 70 arranged to control the supply of steam to two pairs of cylinders. The valves are revolved continuously. Steam is supplied to the hollow interior of each rotating valve by the steam-supply pipes 18 and passes out from 75 it through a single slit, which by the rotation of the valve is first brought opposite to a port leading to one cylinder and afterward opposite to a port leading to another cylinder. In the drawings they are shown to be driven by 80 a bevel-wheel 19, fast with them, gearing into a corresponding pinion on a shaft 20, driven by chain and chain-wheel gear from one of the axles.

For reversing the engine provision is also 85 made for enabling a partial turn to be given to the valve to alter its position relatively to the position of the cranks on the crank-shafts. In the arrangement shown in the drawings this is effected by employing two pinions 21, gearing together and one gearing with a toothed wheel 22, driven by a corresponding wheel which is fast with the chain-wheel driven by the endless chain, and the other with a wheel 23 on the concentric shaft 20. By shifting 95 the pinions 21 around the wheels 22, 23 the valve can have a partial turn given to it without shifting the crank-shafts. This shifting of the pinions around the wheel can be effected by giving an endwise movement to a rod 100 24, which extends back to the foot-plate of the engine.

The exhaust from the cylinders is effected, as shown in Fig. 1, through ports 25 cut in their sides, which become uncovered toward 105 the end of the outstrokes of the pistons, the steam passing out into passages 26 and from thence to the exhaust-pipe 27. The time of cut-off of steam admission can also be varied by giving a partial turn to a sleeve which surrounds such revolving valve. The sleeves can have this partial turn given to them by

arms extending from them, being coupled to a rod which extends back to the foot-plate of the engine.

28 represents cut-off valves for controlling 5 the admission of steam to the rotating valves 17 from the steam-supply pipes 29.

What I claim is—

1. The combination of three parallel crank-axes, cylinders in the spaces between them, 10 pistons working in the cylinders and connections from the pistons to the cranks on the crank-axes, the pistons of the cylinders in the space between the central and one outside axle driving cranks on these axles and those 15 in the space between the central and other outside axle driving other cranks on these axles, so that all three crank-axes are coupled without the use of outside connecting-rods.

2. The combination of three parallel crank-axes, cylinders in the spaces between them, 20 pistons working in the cylinders and connections from the pistons to the cranks on the crank-axes, the pistons of the cylinders in the space between the central and one outside 25 axle driving cranks on these axles and those in the space between the central and other outside axle driving other cranks on these axles, and with the cranks driven by the pistons of one set of cylinders at right angles to the 30 cranks driven by the pistons of the other set.

3. The combination of three parallel crank-axes each having four cranks upon it, two pairs of single-acting cylinders set back to back situated in each of the spaces between 35 the axles, the pistons of one cylinder of each pair in one space coupled by connecting-rods to opposite cranks on the central axle, rods led back from these pistons through stuffing-boxes, means for driving opposite cranks on 40 the adjacent outer axle from these rods and connecting-rods coupling the pistons of the other two cylinders to opposite cranks on this outer axle.

4. The combination of three parallel crank-axes each having four cranks upon it, two 45 pairs of single-acting cylinders set back to back situated in each of the spaces between the axles, the pistons of one cylinder of each pair in one space coupled by connecting-rods 50 to opposite cranks on the central axle, rods

led back from these pistons through stuffing-boxes, means for driving opposite cranks on the adjacent outer axle from these rods and connecting-rods coupling the pistons of the other two cylinders to opposite cranks on this outer axle, and the cranks driven by the pistons of the two pairs of cylinders in one space at right angles to those driven by the pistons of the cylinders in the other space. 55

5. The combination of three parallel crank-axes each having four cranks upon it, two pairs of single-acting cylinders set back to back situated in each of the spaces between the axles, the pistons of one cylinder of each pair in one space coupled by connecting-rods 60 to opposite cranks on the central axle, rods led back from these pistons through stuffing-boxes, means for driving opposite cranks on the adjacent outer axle from these rods and connecting-rods coupling the pistons of the 65 other two cylinders to opposite cranks on this outer axle, and rotary valves driven from and at the same speed as the crank-axes for admitting steam at one time to the two cylinders of one pair and at another time to the 70 two cylinders of the other pair. 75

6. The combination of three parallel crank-axes each having four cranks upon it, two pairs of single-acting cylinders set back to back situated in each of the spaces between 80 the axles, the pistons of one cylinder of each pair in one space coupled by connecting-rods to opposite cranks on the central axle, rods led back from these pistons through stuffing-boxes, means for driving opposite cranks on 85 the adjacent outer axle from these rods and connecting-rods coupling the pistons of the other two cylinders to opposite cranks on this outer axle, rotary valves driven from and at the same speed as the crank-axes for admitting steam at one time to the two cylinders of one pair and at another time to the two cylinders of the other pair, and exhaust-ports in the sides of the cylinders uncovered by the pistons at the end of their outstrokes for effecting the exhaust. 90
